(57) **CLAIM**

The ornamental design for a plastic bag dispenser, as shown and described.

DESCRIPTION

FIG. 1 is a perspective view of a plastic bag dispenser of fully assembled front and back portions.

FIG. 2 is a front view of the plastic bag dispenser of FIG. 1. FIG. 3 is a rear view of the plastic bag dispenser of FIG. 1. FIG. 4 is a left-side view of the plastic bag dispenser of FIG. 1.

FIG. 5 is a right-side view of the plastic bag dispenser of FIG. 1.

FIG. 6 is a top view of the plastic bag dispenser of FIG. 1. FIG. 7 is a bottom view of the plastic bag dispenser of FIG. 1.

FIG. 8 is a perspective view of a front portion of the plastic bag dispenser of FIG. 1, shown separated for ease.

FIG. 9 is a front view thereof.

FIG. 10 is a rear view thereof.

FIG. 11 is a left-side view thereof.

FIG. 12 is a right-side view thereof.

FIG. 13 is a top view thereof.

FIG. 14 is a bottom view thereof.

FIG. 15 is a perspective view of a back portion of the plastic bag dispenser of FIG. 1, shown separated for ease.

FIG. 16 is a front view thereof.

FIG. 17 is a rear view thereof.

FIG. 18 is a left-side view thereof.

FIG. 19 is a right-side view thereof.

FIG. 20 is a top view thereof; and,

FIG. 21 is a bottom view thereof.

The dashed broken lines depict portions of the plastic bag dispenser which form no part of the claimed design.

1 Claim, 21 Drawing Sheets
